LENO-TYPE LOOM ASSEMBLY AND PILE WIRE THEREFOR

Robert O. Sparling, Harmony, R.I.
(20 Austin Ave., Greenville, R.I.)

Filed Jan. 30, 1959, Ser. No. 790,116

8 Claims. (Cl. 139—46)

The present invention relates to improvements in Leno-type looms and more especially to an improved pile wire and improved loom assembly for use with such pile wires.

An object of the present invention is to provide an improved pile wire which can be readily assembled into position in a loom and held in preselected relationship therein for highly efficient formation of pile loops on the ground fabric being woven by the loom.

Another object of the present invention is to provide an improved Leno-type loom assembly and pile wire therefor wherein the pile wires can be easily mounted in position on the loom or removed for replacement as desired.

Still another object of the present invention is to provide an improved Leno-type loom assembly wherein the pile wires therefor are anchored from movement relative to the loom and are supported in preselected relation to components of the loom so as to avoid interference therewith.

Another object of the present invention is to provide an improved Leno-type loom assembly and pile wire therefor wherein the pile wire is independent of the harnesses of the loom and wherein the pile loop forming portion of the wire is resilient so as to be distorted when in operating position so as to allow for free travel of the shuttle.

Still another object of the present invention is to provide an improved Leno-type loom assembly wherein means is provided for supporting the individual pile wires so as to hold the wires in a vertical relationship and to keep the same from twisting objectionably.

A still further object of the present invention is to provide an improved pile wire member which is comprised of two elements joined to form a unit, and wherein one end portion of the pile wire is comprised of a shank formed of thin strip stock adapted to be held in a vertical relationship and from endwise movement, the other end portion of the wire being formed of a simple wire stock integrally joined to the strip of the shank.

A further object of the present invention is to provide an improved pile wire member formed of a shank having a slit in the wire adjacent end thereof which opens out at both surfaces thereof for receiving the respective end of the loop forming wire, the wire diameter and shank thickness being such and so blended at their point as to freely permit the pile forming loops to shed cleanly along the wire and so as to avoid shuttle skips.

Various other objects and advantages will become apparent from the detailed description to follow.

In the drawings:

Figure 1 is a fragmentary view of a Leno-type loom showing my improved pile wire mounted therein in operating relationship;

Figure 2 is a greatly enlarged view of a warp portion of pile fabric showing the manner in which the pile loops are formed over an end portion of my improved pile wire;

2

Figure 3 is an enlarged detail view showing the manner in which a section of wire is joined to a thin, flat strip of stock forming the shank of the pile wire; and

Figure 4 is a bottom view of the pile wire portion of

5 Figure 3.

Referring more particularly to the drawings, wherein like numerals apply to like parts throughout, and having reference first to Figure 1, it will be seen that I have provided an improved pile wire member 10 mounted in a 10 Leno-type loom having a frame including front and rear portions 12 and 14, respectively, with a system of harnesses at 16 including conventional doup heddles at 18. The pile wire member 10 comprises a flat elongated shank 20 substantially rigid in its own plane with an end formation at 22 for anchoring the pile wire member at one end, the other end of the shank having an elongated flexible wire 24 united therewith and extending therefrom with an end portion 26 adapted to be bent for engagement on the ground fabric 28 being woven by the loom and held against the ground fabric by the pile loops 30 being formed thereover.

Referring now to Figures 3 and 4, details of the pile wire member will now be described. The pile wire shank 20 is formed of flat resilient stock with a medially disposed, longitudinally extending slit 32 formed therein, the other edges 34 and 36 of the shank 20 being formed with a taper at 38 and 40 terminating at the slit 32. The slot 32 is of a width corresponding with the diameter of the wire 24 and is of a length to receive a substantial portion of the wire 24 therein. The thickness of the stock for the shank 20 is selected so as also to be preferably thinner than the diameter of the wire 24. The wire 24 is bonded to the shank 20 by brazing, soldering or other suitable methods and then the surface of the shank 20 is ground or buffed so as to be free from projections on the opposite surfaces thereof. The solder or other means used for binding the wire 24 to the shank 20 is shown at 42.

The means 22 for anchoring one end of the shank to the frame of the Leno-type loom is provided by the slot 44 opening out at the side edge 36 of the shank. The slot 44 extends from its open end at 46 toward the terminus 48 of the shank for a reason to be described hereinafter.

The Leno-type loom frame portions 12 and 14 can be conventional portions of the loom as will be obvious. The completed pile fabric passes over the frame portion 12 and out of the loom onto a roll or other suitable collection means also as will be understood by one skilled in the art. The end portion 26 of the wire 24 is resiliently offset downwardly and lies in slightly spaced relation to the ground fabric 28, as best shown in Figure 2, the pile loops 30 being formed thereover and holding the wire portion 26 downwardly under tension over the ground fabric 28. Inasmuch as the shank 20 of the pile member is longitudinally held in a generally horizontal position upwardly offset from the ground fabric 28, the wire 24 is distorted at 50 so as to allow for free travel of the shuttle beneath the whole series of such pile wires.

The shank 20 extends through the system of harnesses 16 and the doup heddles 18 operate in a conventional fashion to pass the pile forming yarn or thread 52 onto opposite sides of the shank 20 so as to form pile loops interlaced with the ground fabric 28 in the fashion shown in Figure 2. The pile loops so formed, of course, pass along the pile wire member.

The construction of the pile wire is such as to permit the yarn to be shed cleanly and easily and also results in avoidance of shuttle skips. Moreover, the design of the pile wire member is such as to diminish the tendency to wear the reeds. Moreover, the substantially flush

mounting of the wire in the flat end of the shank is such as to prevent the loop forming yarn from hankling up on the wire such as would be caused by any projection from the opposite vertical surfaces of the wire member.

Having reference to Figure 1, it will be seen that a rigid cross bar is provided at 54 which is disposed in an upright relationship transversely of the loom. The cross bar 54 is fixedly mounted on the frame portion 14 by means of the angle iron at 56 or in any other suitable fashion, as desired. The rigid cross bar 54 is formed with a multiplicity of vertically disposed slits 58 which correspond in number to the number of pile wire members utilized in the loom. The slits 58 extend in a longitudinal direction so as to receive the shank 20 therethrough to support the latter in a vertical relationship longitudinally of the machine. An anchor rod 60 is provided for engagement in the slots 44 of each of the shanks 20. The anchor rod 60 is substantially rigidly secured in parallel juxtaposition to the cross bar 54. The means for so supporting the anchor rod 60 includes a pair of plates 62 which join the upright cross bar 54 and the angle iron 64 of the frame portion 14 and are secured to the ends of the rod 60.

Inasmuch as the slits 58 open out at the top of the cross bar 54 and the slots 44 open out at the bottom edge of the shanks 20, it will be obvious that the pile wire members can be easily mounted by engaging the shank 20 into a respective slit 58 so that the slots 44 receive the anchor rod 60 therein. During such engagement, the shank 20 will move forwardly and will thereby be substantially held from movement in any direction other than along the axis of the slot 44. Thus, the forces exerted on the pile wire member during weaving of the pile fabric will be substantially opposed. Should replacement of any pile wire member be necessary, it is a simple operation to remove the single pile wire and replace it with another without the necessity for removing any of the other pile wire members.

Further means is provided for supporting the individual pile wires in the desired relationship within the loom. That means includes a support rod 66 which extends transversely of the machine and can be fixedly secured to longitudinal side elements of the frame of the loom in any desired fashion. The support rod 66 is located just rearwardly of the harnesses 16, as is shown best in Figure 1.

From the foregoing, it will be seen a Leno-type loom can receive a multiplicity of my improved pile wire members. The pile wire members are held in a substantially fixed relationship with respect to the loom by the slotted cross bar 54, the anchor rod 22, the support rods 66 and the engagement of the end portion 26 of the wire beneath the loops 39 formed on the ground fabric 28. The flat shank 20 of each pile wire member is held in a selected vertical relationship so as to have the doup heddles pass the loop forming yarn on either side of the shank 20, from which the yarn loops are easily shed toward the front of the loom.

In view of the foregoing it is believed that I have provided an improved pile wire member and Leno-type loom assembly which fulfill the objects hereinbefore enumerated.

As this invention may be embodied in several forms without departing from the spirit or essential characteristics thereof, the present embodiment is therefore illustrative and not restrictive, since the scope of the invention is defined by the appended claims rather than by the description preceding them, and all changes that fall within the metes and bounds of the claims or that form their functional as well as conjointly cooperative equivalents, are therefore intended to be embraced by these claims.

I claim:

1. In a Leno-type loom having a frame, a system of harnesses supported by said frame and having doup heddles carried thereby, at least one pile wire member

comprising a flat, elongated shank substantially rigid in its own plane, means at one end of said shank for anchoring the same to the loom frame, and the other end of said shank having an elongated normally substantially straight, resilient and flexible wire united therewith and extending therefrom with an end portion adapted to be offset for retention in slightly spaced relation over the ground fabric being woven and held in position by the pile loops being formed thereover, an intermediate portion of said flat shank being received through a respective doup heddle of the harnesses so as to have the pile thread looped from side to side of the pile wire member.

2. In a Leno-type loom having a frame, a rigid cross bar anchored to said frame and having at least one vertical slit therein, a system of harnesses supported by said frame and having doup heddles carried thereby, at least one pile wire member comprising a flat, elongated shank substantially rigid in its own plane and having one end engaged through said slit so as to be supported in a vertical relationship, means fixedly anchoring said one end of said shank from movement relative to the frame, and the other end of said shank having an elongated normally substantially straight, resilient and flexible wire united therewith and extending therefrom with an end portion adapted to be offset for positioning in slightly spaced relation over the ground fabric being woven and held in such position by the pile loops being formed thereover, an intermediate portion of said flat shank being received through a respective doup heddle of the harnesses so as to have the pile thread looped from side to side of the pile wire member.

3. In a Leno-type loom having a frame, a rigid cross bar anchored to said frame and having at least one vertical slit therein, a system of harnesses supported by said frame and having doup heddles carried thereby, at least one pile wire member comprising a flat, elongated shank substantially rigid in its own plane and having one end engaged through said slit so as to be supported in a vertical relationship, means fixedly anchoring said one end of said shank from movement relative to the frame, and the other end of said shank having an elongated normally substantially straight, resilient and flexible wire united therewith and extending therefrom with an end portion adapted to be offset for positioning in slightly spaced relation over the ground fabric being woven and held in such position by the pile loops being formed thereover, an intermediate portion of said flat shank being received through a respective doup heddle of the harnesses so as to have the pile thread looped from side to side of the pile wire member, and said means anchoring one end of said shank comprising a rod substantially rigidly secured in parallel juxtaposition to said cross bar, and said one end of said shank having a slot opening out at one side edge thereof for receiving said rod therein.

4. In a Leno-type loom, a frame, a rigid cross bar anchored to said frame adjacent the rear thereof, said cross bar having a multiplicity of vertical slits therein, a system of harnesses supported by said frame forwardly of said cross bar and having doup heddles carried thereby, a support rod rigidly mounted intermediate said harnesses and said cross bar in generally parallel relation to the latter, a multiplicity of pile wire members, at least certain of said pile wire members comprising a flat, elongated shank substantially rigid in its own plane and having one end engaged through a respective slit so as to be supported in a vertical relationship, means for fixedly anchoring said one end of each of said certain pile wire members from movement relative to the frame, an intermediate portion of each of said shanks being engaged on said support rod, and the other end of each said shank having an elongated, resilient normally substantially straight wire joined therewith and axially extending therefrom, said wire being flexible so as to be offset into slightly spaced relation over the ground fabric and held

by the pile loops being formed, said intermediate portion of each of said shanks being received through a respective doup heddle of the harnesses so as to have the pile thread looped from one side to the other of the pile wire member in forming the pile loops.

5. In a Leno-type loom having a frame, a system of harnesses having doup heddles carried thereby and supported by said frame at a longitudinally medial portion of the loom, a rigid cross bar transversely anchored to said frame adjacent the rear thereof and having a multiplicity of vertical slits therein, a multiplicity of pile wire members, each of said pile wire members being of a length extending from about said rigid cross bar to the front of the frame and including a shank and a wire, each said shank being formed of flat stock substantially rigid in its own plane having one end thereof engaged through a respective slit in said rigid cross bar so as to be held in a vertical relationship and having the other end thereof engaged through a respective doup heddle of the harnesses, means connected with the frame supporting said shanks adjacent the system of harnesses, means at said one end of said shanks for anchoring the same from end wise movement relative to the frame, and each said wire being formed of flexible resilient stock with one end fixedly joined to said shank and its other end terminating at the front of the frame and being adapted to be resiliently offset into slightly spaced relation to the ground fabric and held thereon by the pile loops formed thereover.

6. In a Leno-type loom having a frame, a system of harnesses having doup heddles carried thereby and supported by said frame at a longitudinally medial portion of the loom, a rigid cross bar transversely anchored to said frame adjacent the rear thereof and having a multiplicity of vertical slits therein, a multiplicity of pile wire members, each of said pile wire members being of a length extending from about said rigid cross bar to the front of the frame and including a shank and a wire, each said shank being formed of flat stock substantially rigid in its own plane having one end thereof engaged through a respective slit in said rigid cross bar so as to be held in a vertical relationship and having the other end thereof engaged through a respective doup heddle of the harnesses, first means connected with the frame supporting said shanks adjacent the system of harnesses, second means at said one end of said shanks for anchoring the same from endwise movement relative to the frame, each said wire being formed of flexible resilient stock with one end fixedly joined to said shank and its other end terminating at the front of the frame and being adapted to be offset into slightly spaced relation to the

ground fabric and held thereon by the pile loops formed thereover, said first means including a support rod substantially rigidly mounted in spaced parallel relation to said cross bar, and said second means including an anchor rod substantially rigidly secured in parallel juxtaposition to said cross bar, and said one end of each of said shanks having a slot opening out at one side edge thereof for removably receiving said anchor rod therein.

7. A pile wire member comprising a shank of predetermined length having top and bottom edges and being formed of a thin, flat strip, one end of said shank having a slot formation therethrough of a selected width opening out at said bottom edge thereof adapted to receive an anchor rod therein of a diameter corresponding to said selected width, the inner end of said slot formation being disposed closer to the terminus of said one end of the shank than the open end thereof so that the anchor rod-receiving inner end is completely longitudinally offset from the open end, the opposing end of said shank having an axially extending slit opening out on opposite surfaces thereof and at the terminus of said opposing end, and an elongated resilient wire received in said slit and permanently joined to said shank.

8. A pile wire member comprising a shank of predetermined length having top and bottom edges and being formed of a thin, flat strip, one end of said shank having a slot formation therethrough of a selected width opening out at said bottom edge thereof adapted to receive an anchor rod therein of a diameter corresponding to said selected width, the inner end of said slot formation being disposed closer to the terminus of said one end of the shank than the open end thereof so that the anchor rod-receiving inner end is completely longitudinally offset from the open end, the opposing end of said shank having an axially extending slit opening out on opposite surfaces thereof and at the terminus of said opposing end, and an elongated resilient wire of a diameter slightly greater than the thickness of said shank received in said slit, and means permanently joining said wire to said shank filling the remaining space between said wire and the shank within said slit so as to be substantially free of projections.
